UNITED STATES PATENT OFFICE.

JOSIAH JEWETT, JR., OF BUFFALO, NEW YORK.

DESIGN FOR A COOKING-RANGE.

46,052.

Specification for Design.

Patented July 7, 1914.

Application filed April 24, 1914. Serial No. 834,214. Term of patent 14 years.

To all whom it may concern:

Be it known that I, JOSIAH JEWETT, Jr., a citizen of the United States, residing at Buffalo, in the county of Erie and State of New York, have invented a new, original, and ornamental Design for Cooking-Ranges, of which the following is a specification, reference being had to the accompanying drawing, forming part thereof.

The figure is a perspective view of a cooking range, showing my new design.

I claim:

The ornamental design for a cooking range, as shown.

JOSIAH JEWETT, JR.

Witnesses:

EDWARD WILHELM,
C. B. HORNBECK.
